Application August 8, 1930. Serial No. 473,917

11 Claims. (Cl. 164—99)

This invention relates to a punching or slotting machine and more particularly to a machine for slotting elongated strip material such, for example, as metallic tape or the like.

5 An object of this invention is to provide a machine of the type set forth constructed and arranged to operate continuously upon elongated strip material.

This and other objects which will be apparent to those skilled in this particular art are obtained by means of the invention illustrated in the accompanying drawings in which—

10 Fig. 1 is a side view in elevation of a machine constructed in accordance with one embodiment 15 of this invention.

Fig. 2 is a similar view taken from the left of Fig. 1.

Fig. 3 is an elevation taken from the right of Fig. 1.

20 Fig. 4 is a top plan view.

Fig. 5 is a partial sectional view, on an enlarged scale, of a portion of the machine showing the arrangement of the die rollers.

Fig. 6 is a view in elevation taken from the 25 right of Fig. 5.

Fig. 7 is a transverse sectional view showing the driving gears for the various rollers.

Fig. 8 is a sectional view showing the eccentric mounting for one of the ironing rollers.

30 Fig. 9 is a transverse sectional view on the line 9—9 of Fig. 8.

Fig. 10 is an enlarged section through the perforating or slotting rollers.

Fig. 11 is a similar view to still larger scale 35 through a portion of the rollers illustrating the slotting operation.

Fig. 12 is a transverse section through the punch and die rolls.

Fig. 13 is an elevation of the tape stripping 40 mechanism shown in Fig. 12.

Fig. 14 is a vertical sectional view through the take-up reel.

Fig. 15 is a sectional view of the mechanism on the line 15—15 in Fig. 14, and

45 Fig. 16 is an enlarged fragmental view illustrating the formation and operation of the cutting punches.

The particular embodiment of the present invention which has been chosen for the purposes 50 of illustration comprises a machine which is specially arranged to cut elongated slots in metallic tape such as is used, for example, in the manufacture of certain forms of cables or the like. As illustrated, the machine is provided with rotary punching dies or rollers which operate con-

tinuously upon the tape and at a relatively high speed. The punch roller is operated by the movement of the tape itself through the dies in contact therewith, and suitable mechanism is employed for drawing the tape past the rotary 60 punching die and collecting the punched material upon a take-up reel, the latter being operated by mechanism having certain novel features. The die rollers are of novel construction and capable of operating at comparatively high 65 speed.

The illustrated machine has a punching roll 20 provided with a plurality of metal punches or teeth 21 positioned thereon in circumferential rows and supported upon a shaft 22 freely rotatable in suitable bearings in a housing 23 slidably mounted on a supporting base 24 and adjustable thereon through the medium of an adjusting thumb screw 25 for shifting the housing upon the supporting base. Suitable clamping 70 nuts 26 of standard form are employed for clamping the housing 23 and punching roll in the desired position. A die roller 27 is secured to a shaft 28 positioned in the base 24 and is formed with a plurality of circumferential grooves 29 80 adapted to receive the punch teeth 21 during the punching operation, the die roll 27 forming a support for the tape 30 during the punching thereof.

A pair of feed rolls 31 are supported upon feed roll shafts 32 in the housing 24 and are so positioned as to engage the perforated tape after it has passed through the punch dies. The rolls 31 engage the tape with sufficient pressure to draw the same through the punching dies and around the punching roll 20, the latter being 90 rotated by the movement of the tape resulting from operation of the feed rolls 31. The latter are operated from a power shaft 33 driven by any suitable source of power such as an electric motor 34. A helical gear 35 on the power shaft 33 95 drives a similar gear 36 secured to the lower feed roll shaft 32 geared to the upper feed roll shaft by suitable gears 37 so that the feed rolls 32 operate to draw the tape 30 from a supply roll 38 over the die roll 27, between the die roll and 100 the punching roll 20, around the punching roll 20 through the feed rolls and deliver it to a take-up mechanism hereinafter described.

The upper feed roll gear 37 drives a gear 39 on the die roll shaft 28 through a suitable idler gear 40, and the pitch diameters of the respective gears are such that the die roll 27 is driven at a peripheral speed that exceeds slightly the speed of travel of the tape 30 and hence the peripheral speed of the punching roller 20. As a result of 110

this arrangement the die roll is so operated as to present a constantly changing face to the punching roller, thus distributing wear evenly around the entire circumference of the die roller 27. At the same time, this operation prevents the punchings or slugs which are punched from the tape from piling up and packing in the slots of the die roll in such a way as to prevent their removal. Positively driving the die roll also insures removal of the slugs by the slug removing comb hereinafter described. The die roll being, in effect, a cutting die it will in time become dull, necessitating regrinding. Such regrinding will reduce its diameter and therefore its peripheral speed. Should this peripheral speed ever become less than the speed of travel of the tape, which is determined by the speed of the feed rolls, it would produce a very undesirable drag upon the tape, somewhat in the manner of a brake drum. However, by driving the die roll at a greater speed than the speed of travel of the tape, the above undesirable possibilities are forestalled. Also, positively driving the die roll 27, material assistance is given to the feed rolls in drawing the tape off the supply reel, and rotation of the die roller, and the resulting punching operation is also aided.

The feed rolls 31 preferably perform the additional function of ironing or burnishing the slotted tape. The upper roll shaft 32 is mounted in bearings 41 located in an eccentric bearing support 42 rotatably positioned in the housing 24. An arm 43 is connected to the eccentric support 42 and is drawn downwardly by a suitable spring 44 so as to press the upper feed roll 31 yieldingly downward to produce an ironing pressure of the feed rolls upon the tape.

A pronged stripper plate 45, see Figs. 12 and 13, is located below the punch roll and has its prongs or fingers 46 positioned so as to strip the punched tape from the roll and direct it to the feed rolls. In order to remove any punchings which may cling to the tape due to not being cut clear, a scraper 47 is provided for scraping the surface of the tape as it is stripped from the punch roll. The scraper may be formed from one or more flat pieces of spring steel bent to form, and so positioned as to bear yieldingly against the surface of the tape. The scrapers are preferably of gooseneck formation so that they will spring away from the tape and not dig in, should they catch upon the tape surface for any reason.

The punched slugs 48 which are deposited in the slots of the die roll 27 are removed by a suitable comb 49 or the like which removes the slugs from the grooves upon rotation of the roll and drops them into a chute 50. Positive rotation of the die roll insures removal of the slugs by the comb.

It will be apparent that the grooved die roll 27 provides an ever changing die surface which supports the tape being punched at the sides only of the slots which are formed therein, the slotted portion being unsupported during the punching operation at the ends of the slots.

In view of the fact that the two die rolls are rotated at different peripheral speeds, it is important to position them so that the punching roll does not press the tape tightly against the die roll 27, so as to avoid friction loss and possible distortion of the tape. At the same time, as in any punching operation, the tape should be quite closely confined or held down upon the die surface. Adjustment of the thumb screw 25 per-

mits the proper positioning of the two rolls relatively to each other and renders it possible to obtain a close confinement of the tape between the rolls without undue pressure. Relative lateral movement of the die rolls is prevented by 80 annular flanges 51 formed preferably on the punch roll which engage shoulders 52 on the die roll, see Figs. 10 and 11.

As most clearly illustrated in Figs. 10 and 11, the die roll 27 is built up of a plurality of discs 85 53 separated by spacers 54, the assembly being clamped on a support 55 secured to the shaft 28. The diameter of the spacers 54 is such, in comparison to the diameter of the discs 53, as to provide the necessary circumferential slots 29 of 90 sufficient depth to accommodate the punch teeth 21 of the roller punching die and the punched slugs 48 from the tape. The punch roller is built up by a plurality of discs 56 separated by spacers 57 which are of such diameter relatively 95 to the discs 56 as to provide a series of circumferential grooves 58 in which the annular punch rings 59, on which the punch teeth 21 are formed, are accommodated. Each punch ring 59 can be easily stamped or otherwise formed from suitable sheet material and is preferably provided with an odd number of cutting teeth 21. Diametrically opposed holes 60 are formed in each punch ring, one hole being positioned opposite a tooth and the other hole opposite a space between 105 adjacent teeth. With such an arrangement, it will be apparent that the punch rings can be mounted upon the punch roll so that the teeth of one ring are staggered with relation to the teeth of the adjacent rings, as more or less dia- 110 grammatically illustrated in Figs. 3 and 6. Suitable blocking pins 61 are employed for locking the parts together against relative circumferential movement. In order to provide for possible variations in the thickness of the punch rings 59 115 the spacers 57 and discs 56 are very accurately sized, and the spacers 57 are equal in thickness to the thickest of the punch rings 59. As a result, the latter may have a very small lateral play in the grooves 58, depending upon their 120 thickness, and thus automatically adjust or center themselves in the slots of the die roll 27.

The individual teeth 21 are so formed as to pierce the tape at each end of each slot and to then cut the center portion between the two 125 pierced points. The prong or point at the leading end of each tooth is lower, or may be lower, than the prong at the following end of each cutting edge. This produces piercing at the ends of each slot first and this shape of tooth is also 130 beneficial in enabling the tape to be stripped from the teeth without stretching or tearing.

From the ironing rolls or feed rolls 31, the perforated tape is delivered to a suitable take-up mechanism which is of such construction that the take-up reel is rotated in a manner to maintain the tape under a substantially constant tension. As illustrated, the tape passes around an idler 61' before being delivered to the take-up reel 62. The reel is supported upon a drive shaft 63 driven from the power shaft 33 through suitable gearing 64. A band type driving clutch drum 65 is secured to the reel shaft 63 and the reel itself is mounted upon a roll supporting member 66 supported on a bearing 67 so as to 145 be freely rotatable with relation to the shaft 63. A pin 68 mounted in the lower face of the reel support 66 extends downwardly through a slot 69 in an intermediate control drum 70 and has its lower end connected to one end of a clutch 150

band 71 extending around the lower driving clutch drum 65 and connected at its opposite end to a pin 72 secured to the intermediate control drum 70. A brake band 73 surrounds the intermediate control drum 70 and is connected at one end to a pin 74 mounted on the machine frame, see Fig. 15, and at its other end to one arm of a lever 75 pivoted at 76 to the machine frame and supporting on its other arm the idler roller 61'. A spring 77 tends to draw the lever into brake releasing position while any increased tension on the tape 30 tends to swing the lever so as to apply the brake band 73.

The operation of the take-up mechanism is such that the speed of rotation of the reel is dependent upon the frictional engagement of the clutch band 71 on the lower clutch drum 65 which is secured to the operating shaft, and this frictional engagement is varied by the position of the intermediate control drum 70 with relation to the pin 68. The position of the drum 70 is in turn a function of the tension of the tape which operates through the lever arm 75 to control the pressure of the brake band 73 on the drum 70 and thus to so control the position of the drum 70 relatively to the pin 68 as to maintain the necessary frictional engagement of the clutch band 71 upon the driving clutch drum 65 to produce such a rotation of the take-up reel as will maintain a substantially constant tension upon the perforated tape.

A hand wheel 78 is preferably provided upon the roller die supporting shaft 22 so that the end of the tape 30 can be properly threaded through the opening between the dies and around the roller die into engagement with the feed rolls 31. The proper position of the punching roller relatively to the die roller 27 is obtained by suitable manipulation of the adjusting thumb nut 25 after which the parts are secured in adjusted position by the clamp nuts 26. It may be desirable to provide the power shaft with any of the well-known forms of accelerating devices to produce a gradual acceleration of the machine under the impulse of the driving motor, so as to prevent the machine attaining full speed so rapidly as to break the tape. Operation of the feed rolls and rotation of the die roll 27 draws the tape off the supply reel, over the die roll, between it and the punch roll, thence around the punch roll which is thereby rotated, past the stripper mechanism and the scraper and through the feed rolls 31 where it is ironed and burnished to finished form. By driving the punching roll 20 through the medium of the tape itself, all necessity for any delicate timing mechanism or adjustment of parts to prevent tearing of the tape by the punch roll is eliminated.

Although I have described a specific embodiment of this invention in more or less detail it will be apparent that various changes, additions, omissions and substitutions may be made therein without departing from the spirit of this invention or the scope of the appended claims.

65 What I claim as new and desire to secure by Letters Patent is:

1. The combination in a punching machine for punching metallic tape of a punching member, a slotted die member, means for passing tape between said members and means for rotating said members relatively to each other to provide a fresh supporting surface for said tape during succeeding punching operations.

2. The combination in a punching machine for slotting metallic tape of a rotary punching mem-

ber having slotting punches provided thereon, a roller die provided with a plurality of circumferential slots for receiving said punches and means for rotating said die so that the circumferential speed thereof is greater than the circumferential speed of the punching member. 80

3. The combination in a punching machine of a rotary punching member having a plurality of punches extending radially therefrom, a roller die co-operating therewith and provided with circumferential slots for receiving said punches, a pair of feed rolls for continuously drawing tape between said die and member arranged so that the tape passes partially around said punching member to rotate said member and means for rotating said roller die at a greater circumferential speed than the speed of travel of said tape. 85

4. The combination in a punching machine of a rotary punching die arranged to be rotated by movement of the work, a work supporting roller die having circumferential slots co-operating with the punches of said roller die, means for positively driving said roller die, work feeding rolls engaging the punched work and arranged to draw the work between said dies, whereby said punching die is rotated, means for yieldingly pressing said feed rolls upon the work. 90

5. The combination in a punching machine of a rotary punching die arranged to be rotated by movement of the work, a work supporting roller die having circumferential slots co-operating with the punches of said roller die, feed rolls for drawing work between said dies, means for driving said feed rolls and means connecting said driving means to said roller die for rotating said die at a greater circumferential speed than the circumferential speed of said feed rolls. 100

6. The combination in a punching machine of a rotary punching member having a plurality of punches extending radially outward therefrom, and means for supporting said punches to permit limited movement thereof axially of said member. 115

7. The combination in a machine for punching metallic tape of co-operating rotary punching dies, a pair of feed rolls for passing tape through said dies, a take-up reel, means for rotating said feed rolls and said reel, and means for controlling the rotation of said reel so as to maintain a substantially constant tension on said tape. 120

8. The combination in a machine for punching metallic tape of co-operating rotary punching dies, a pair of feed rolls for passing tape through said dies, a take-up reel, a power shaft, means for driving said feed rolls from said power shaft, means for driving said take-up reel from said power shaft and means responsive to variations in the tension on said tape for controlling the rotation of said take-up reel so as to maintain a substantially constant tension on said tape. 125

9. The combination in a punching machine for continuously operating upon metallic tape including a pair of rotary punching dies and means for drawing tape through said dies including a take-up reel, a shaft for rotating said reel, a flexible connection between said shaft and said reel, and means for controlling said connection including a spring pressed lever responsive to variations in the tension of the tape. 135

10. The combination in a punching machine for continuously operating upon metallic tape including a pair of rotary punching dies, means for continuously drawing tape through said dies including a take-up reel, a power shaft for rotating said reel, a clutch drum secured to said shaft, a flexible connection between said brake drum 145

and said reel including a clutch band co-operating with said drum, means for varying the pressure of said band on said drum including a second drum rotatable with said reel, a brake band for controlling the operation of said second drum and means for varying the effect of said brake band by and in accordance with variations in the tension on said tape.

11. The combination in a punching machine
10 of a rotary punching member having a plurality

of punches extending radially therefrom, a roller die co-operating therewith provided with circumferential slots for receiving said punches, a pair of feed rolls for continuously drawing said tape between said die and said member, an eccentric 80 mounting for one of said feed rolls and means associated therewith for yieldingly pressing the eccentrically mounted roll against its associated feed roll.
